FINGER RING AND METHOD OF MAKING

Garnet P. Grant, Plandome, N. Y.

Application June 23, 1936, Serial No. 86,733

17 Claims. (Cl. 63—15)

This invention relates to finger rings and the method of making the same.

It is desirable to produce rings into which may be introduced a picture of a person or some other form of personal, individual ornamentation. In order to be practical the ring must be finally assembled at the point of sale. This is necessary in order to incorporate in the ring a picture or other ornamentation selected by the purchaser.

In the past, where such procedure has been attempted the results have been unsatisfactory. The practice has been to place a picture in a setting and cover the picture with a transparent cap of glass or other material held in place by a bezel. The bezel and cap are cemented to the ring at the time of sale. Such rings are usually sold as novelties and assembled by inexpert workers. Rings made as above outlined are unsatisfactory for the reason that the joint between the ring and the bezel is not permanent or waterproof and the ring quickly comes apart. Furthermore, the junction between the two parts is exposed and is unattractive, particularly where the assembly is made by an inexpert worker such as might easily be found where such novelties are sold but not manufactured.

Therefore, one object of the present invention is to provide a ring into which an ornamentation selected by the purchaser may be inserted and which ring may be finally assembled at the point of sale to produce a waterproof, permanent, attractive product without the need of skilled labor.

A further object of the invention is to provide a simple, effective method of making and assembling such a ring.

The ring may be made of any desired material. Where the rings are sold as novelties or souvenirs it has been found very satisfactory to use celluloid or a cellulose product or one of the many synthetic hard rubber compositions commercially available.

The invention consists of the construction, combination, arrangement of parts and the steps of the method, as herein illustrated, described and claimed.

In the accompanying drawings, forming part hereof, are illustrated two embodiments of the invention, in which drawings similar reference characters designate corresponding parts, and in which:

Figure 1 is an elevation, partly in section, with the parts shown in separated position;

Figure 2 is an elevation, partly in section, of the assembled ring;

Figure 3 is a vertical section through a different plane of the assembled ring;

Figure 4 is a plan view showing one shape of ring without any ornamentation;

Figure 5 is a plan view of a different shape of ring showing the ornamentation;

Figure 6 is a vertical section of a different form of ring, the parts being shown separated;

Figure 7 is a perspective of a tube from which ring blanks may be cut;

Figure 8 is a vertical section taken approximately on line 8—8 of Figure 7;

Figure 9 is a vertical section, taken longitudinally of the tube in Figure 7, one ring blank being separated;

Figure 10 is a vertical section showing the partly formed ring blank;

Figure 11 is a vertical section, showing a further stage in the formation of the ring;

Figure 12 is an elevation of the finished ring;

Figure 13 is a vertical section through the finished ring; and,

Figure 14 is a plan view of the finished ring.

Referring to the drawings, and particularly to Figures 1 to 5, 15 designates a ring which may be an ordinary, plain circle of any desired cross-section. Secured at any point of the circumference of the ring 15 is a block 16 having a curved recess 17 to fit the curvature of the ring 15. The two parts may be secured together in any suitable manner and are made as a subassembly at the factory or other place of production of the rings. If the material used is celluloid or a similar material, the members 15 and 16 may be permanently secured together by brushing the contiguous surfaces with acetate or a solution of celluloid in acetate which will permanently bond the two members together to make an integral whole. The block 16 may be round, oval, square or any other desired shape which the finished ring may have.

Disposed over the block 16 is a cap 18. The cap 18 is preferably made of a plurality of layers of differently colored material. Centrally of the cap 18 is provided an opening 19 of a size and shape to receive the block 16 upon the final assemblage of the ring. The cap 18 has superposed thereon a cover 20 of transparent material. The cover 20 and the cap 18 are secured together as a subassembly by any appropriate cementitious agent. If the materials used are celluloid or a related product, a permanent bond between the cap 18 and the transparent cover 55

20 may be formed by using acetate together with the application of pressure, with or without heat. In this way the parts are joined together as one piece.

5 The subassembly of the cap 18 and the cover 20 is then beveled as shown at 21 in Figure 2 and any desired polishing or buffing is applied to the cap. When the cap 18 is beveled the various colors in the several layers of the cap 10 18 will appear as concentric lines to effect a decoration of the ring.

The two subassemblies comprised by the ring 15 and the block 16, and the cap 18 and cover 20, are now ready for distribution to the eventual user. At the point of sale a picture 22 or other form of relatively flat ornamentation is inserted in the opening 19 of the cap 18. The block 16 is inserted in the opening 19 underneath the picture 22 and supports the picture 22. The block 16 and cap 18 are held together by any suitable cementitious agent. As above pointed out, if the materials of the ring are celluloid, an acetate solution will make a permanent, waterproof bond between the parts.

25 The advantage of the foregoing construction over the prior art will be clear. In the first place, the cap 18 and cover 20 are assembled as a unit at the factory and are thereafter finished to provide an attractive appearance. The final 30 assembly at the point of sale may be made by a relatively unskilled worker, but nevertheless the joint between the two parts of the ring will not show and there is no danger of the cover 20 becoming loose from the cap 18 by reason of improper assembly at the point of sale.

In connection with the point of sale, it may be stated that the rings described herein are frequently sold in photographic studios that produce a strip of pictures for a small sum of 40 money. The customer will select one of the pictures of himself or of someone else and the head portion of such picture will be cut to fit the shape of the ring and will be assembled then and there. The rings are sold also at tourist 45 sorts, and instead of a photograph of an individual the picture 22 may be one of a building or other item of public interest. Of course, other forms of ornamentation may be readily used instead of pictures. Therefore, it will be 50 appreciated that it is essential to have a ring which may be easily assembled by an unskilled worker and which will nevertheless be permanent and present a pleasing appearance.

Referring to Figures 6 to 14, 24 designates a 55 tube of suitable material having one side formed with a plane surface. Disposed on the plane surface of the tube 24 is a strip 25 formed of a plurality of layers, preferably of varying colors. The strip 25 and the tube 24 may be joined 60 together in any appropriate manner it being preferable to use a cementitious agent under pressure, with or without the application of heat. Along the length of the tube 24 a plurality of openings 26 are formed through the strip 25 and tube 24. These openings may be either punched or drilled depending upon the 65 nature of the material used.

The next step is to apply a transparent cover which is put on in the form of a strip 27 and 70 is secured to the strip 25 in the same manner as heretofore described in connection with the other parts. This provides an absolutely waterproof pocket formed by the opening 26 which may receive a picture or other ornamentation.

75 The tube 24 is then cut into sections to form

ring blanks 28, as shown in Figure 9. The blank 28 is then shaped on its lower part to approximately the thickness desired at the bottom of the ring, as shown in Figure 10, to produce a finished ring 29. The upper part of the ring is 5 then beveled as shown at 30 in Figure 11, and any desired buffing or polishing is applied.

This produces a one piece ring having a transparent top 27 and a series of concentric lines 25 10 to provide an attractive appearance. A picture or other ornamentation 32 is inserted into the pocket formed by openings 26 and the opening 26 is closed by a plug 31. If the openings 26 had originally been formed by punching, the plug 31 might well be the plug removed originally 15 to form the opening 26. If the opening 26 had originally been drilled a separate plug 31 must be provided.

The rings are completely finished at the factory, in various sizes, with the exception that 20 the plug 31 is not inserted in the opening 26. At the point of sale, when the customer has selected a picture or other ornamentation, it is necessary that the picture 32 be inserted in the opening 26 and held in place by the insertion of 25 the plug 31. Of course, the plug 31 will be cemented into the opening 26 in any desired manner, as previously pointed out. This construction provides a waterproof joint, and eliminates the possibility of the picture 32 coming 30 out of the ring 29, or the upper part of the ring becoming separated by reason of poor assembly at the point of sale.

Furthermore, it will be clear that an attractive ring may be readily assembled, even though 35 the person who does the work may be very inexpert.

Having thus fully described the invention, what is claimed as new, and desired to be secured by Letters Patent of the United States, is:

1. A finger ring having a portion to encircle a finger, a top portion formed of a plurality of sheets with a central opening therein, the edges of the top portion being beveled to show the several layers, and a transparent cover secured 45 to the top portion and covering the central opening.

2. A finger ring comprising a ring to encircle a finger, a block carried by the ring, a cap formed of a plurality of layers disposed over the 50 block, said cap being formed with a central opening to receive the block and a transparent cover secured to the cap.

3. A finger ring comprising a ring to encircle a finger, a block carried by the ring, a cap 55 formed of a plurality of layers disposed over the block, the edges of said cap being beveled to show the several layers and said cap being formed with a central opening to receive the block and a transparent cover secured to the 60 cap.

4. The method of making finger rings which consists in forming a ring and securing a block thereto, forming a cap portion of a plurality of layers, forming an opening in the cap portion to receive the block, securing a cover over the opening on the cap and finally assembling the cap and ring into a single unit.

5. The method of making finger rings which 70 consists in forming a ring and securing a block thereto, forming a cap portion of a plurality of layers, forming an opening in the cap portion to receive the block, securing a cover over the opening on the cap, beveling and finishing the 75

cap and cover and finally assembling the cap and ring into a single unit.

6. The method of making finger rings which consists in forming a ring and securing a block thereto, forming a cap portion of a plurality of layers, forming an opening in the cap portion to receive the block, securing a cover over the opening on the cap, beveling and finishing the cap and cover, inserting an ornament in the cap beneath the cover and finally assembling the cap and ring into a single unit.

10 7. The method of making finger rings which consists in forming a ring and a cap receiving block as a sub-assembly, forming a cap of a plurality of layers and securing a cover thereto as a second sub-assembly, inserting an ornament under the cover and finally assembling the two sub-assemblies into a finished ring.

15 8. A finger ring having a portion to encircle a finger and a top portion formed of a plurality of layers, the top portion having a central opening therethrough, and a transparent cover secured to the top portion over the central opening.

20 9. A finger ring having a portion to encircle a finger and a top portion formed of a plurality of layers, the ring and top portion having a central opening therethrough, a transparent cover secured to the top portion over the central opening and a plug to fill the central opening.

25 10. A finger ring having a portion to encircle a finger and a top portion formed of a plurality of layers, the ring and top portion having a central opening therethrough, a transparent cover secured to the top portion over the central opening, an ornament disposed in the central opening and a plug to fill the central opening.

30 11. The method of making finger rings which consists in forming a ring blank, securing a multiple layer cap on the blank, forming an opening through the ring and cap, securing a cover on the cap over the opening and finally forming the parts into a finished ring.

35 12. The method of making finger rings which consists in forming a ring blank, securing a multiple layer cap on the blank, forming an opening through the ring and cap, securing a cover on the cap over the opening, reducing the body of the ring blank to desired shape and beveling and polishing the cap portion.

13. The method of making finger rings which consists in forming a ring blank, securing a multiple layer cap on the blank, forming an opening through the ring and cap, securing a cover on the cap over the opening, reducing the body 5 of the ring blank to desired shape, beveling and polishing the cap portion and inserting an ornament in the opening.

14. The method of making finger rings which consists in forming a ring blank, securing a multiple layer cap on the blank, forming an opening through the ring and cap, securing a cover on the cap over the opening, reducing the body 10 of the ring blank to desired shape, beveling and polishing the cap portion, inserting an ornament 15 in the opening and inserting a plug in the opening to maintain the ornament in place.

15. The method of making finger rings which consists in forming a tube with a plane surface, securing to the plane surface a multiple layer 20 strip, forming openings through the strip and tube at intervals along the tube, securing a cover piece over the multiple strip and openings, cutting the tube into ring blanks, forming the body of the blank to desired shape and beveling 25 and polishing the multiple strip and cover.

16. The method of making finger rings which consists in forming a tube with a plane surface, securing to the plane surface a multiple layer 30 strip, forming openings through the strip and tube at intervals along the tube, securing a cover piece over the multiple strip and openings, cutting the tube into ring blanks, forming the body 35 of the blank to desired shape, beveling and polishing the multiple strip and cover and inserting an ornament in the opening under the cover.

17. The method of making finger rings which consists in forming a tube with a plane surface, securing to the plane surface a multiple layer 40 strip, forming openings through the strip and tube at intervals along the tube, securing a cover piece over the multiple strip and openings, cutting the tube into ring blanks, forming the body 45 of the blank to desired shape, beveling and polishing the multiple strip and cover, inserting an ornament in the opening under the cover and inserting a plug in the opening to seal the ornament in position.
